HELEN ALSTON TAYLOR, OF NEW YORK, N. Y.

HAIR WAVING MEANS

Application filed September 11, 1930. Serial No. 481,274.

My present invention relates to an improved method and means for waving hair, especially waving the hair at the ears, and forms a useful and advantageous contribution and adjunct to the art of hair-waving including finger waving, so-called, and the like.

The object of the invention is to permit the hair at the ears to be waved more perfectly as well as more quickly than is ordinarily possible by the present methods, it being understood that this is the most difficult part of the hair to wave.

Another object is to cause the waved and still wet hair at the ears to dry more quickly under the application of heat than is possible by the present methods, it being understood that this is ordinarily the last portion of the hair to dry.

20 The invention as a method comprises the combination of steps and as a means or device comprises the combination of elements herein set forth and claimed. The invention will be understood from the following description in connection with the drawings disclosing a specific embodiment of the invention which, however, it will be understood, is put forward simply as illustrative of the invention and not as limiting it to the details 25 of said embodiment except as may be required by the claims.

As a device, the invention comprises a cover fitting over the ear forming a surface sufficiently continuous with the head against which the operator can press, comb and manipulate the hair as though the ear were not there; and in its preferred form another object of the invention is to render the device sanitary by making the part of the device 35 which contacts the ear detachable so that after use it may be discarded and substituted by a fresh part.

These and other objects of the invention will appear from the following description 40 in connection with the drawings already referred to.

In the drawings, Fig. 1 is a perspective of an ear cover within my invention, the two parts thereof being shown separated; Fig. 2 45 is a vertical section on the line 2—2 in Fig. 3

showing the parts of the ear cover assembled and suspended on the ear of the user; Figs. 3 and 4 are views respectively of the inside and outside of the ear cover, the latter showing the ear in dotted outline under the cover; and Fig. 5 is a cross-sectional view on the line 5—5 in Fig. 3 looking in the direction of the arrows.

This illustrated ear cover is in two parts, namely, an inner part 1 of felt, fabric, paper, paste-board, or the like, adjacent the ear; and an outer part 2 consisting of a thin sheet or plate preferably of a metallic or heat-absorbing and reflecting material, such as polished aluminum for example. The material of the part 1 may comprise any sufficiently heat-insulating material for protecting the ear from the heat absorbed and reflected by the metallic plate 2 during the drying heat treatment of the hair to set the wave after it has been formed.

In area, the device should preferably be considerably larger than the ear so that when in position it extends laterally well beyond the ear towards the front and back of the head. It is also desirable that it should extend above and below the ear. The plate 2 either has or assumes, when in position over the ear, an outwardly convex form and provides a surface sufficiently continuous with the head for the operator to work against without interference from the ear.

The parts 1 and 2 may be permanently united, but by preference are semi-permanently or detachably united as by a drop of glue or cement or, as shown in the drawings, by a clip 3 consisting of a bent-over portion of the metallic plate adapted to releasably engage a lip or flange 4 formed on the inner part 1.

The device may be supported at the ear in any way practical in this connection but I prefer to support it on or by the ear itself. Moreover, I prefer to make the supporting means such that the device can be inserted up under the hair and attached to the ear before beginning to wave the hair at the ear. For this purpose, in the illustrated device, the inner part 1 is formed at the top with a downwardly opening pocket 5 formed between the

body of the part and a flap 6 secured thereto at its top and ends. This flap is made of springy material or embodies a strip 7 of springy material or any material tending to 5 keep the mouth of the pocket open. The pocket is shaped to slip over and receive into it the top of the ear and thereby support the device in covering position on the ear.

The illustrated inner part 1 when described 10 in great detail comprising a single piece of felt or fabric having a main portion 1^a of similar shape but preferably somewhat larger area than the metal plate 2. An integral continuation 1^b from the top of said main portion is folded down upon the main portion 1^a and then half of this is folded upwardly again as at 1^c. A strip of aluminum 7 or, other suitable more or less stiff material is laid in the fold thus formed. Then an accurate line of stitching 8 is applied through said main folded portions over the top and ends of the stiffened insert 7 to form the heretofore referred to downwardly opening pocket 5 whose mouth tends to remain open 15 for hooking over the top of the ear. The heretofore referred to lip or flange 4 adapted to be gripped by the clip 3 of the metal plate 2 consists, it will be seen, of that part of the first fold which is located between the edge 20 of the fold and the stitching 8.

My method of hair waving and the utility of the described device can now be readily understood. The operator, having waved the wetted hair down to the ears, will insert 25 the device up under the pendent hair and hang it over the ear, metal side outermost. The operator will then press, comb and manipulate the hair against the device which it is perfectly easy to do because it is a flat 30 smooth surface comparable to the other portions of the head where the operator can work against the scalp. This is a great advantage over the ordinary methods where the operator, to avoid interference by the ear, divides 35 the hair and waves it in two parts, one ahead and the other in back of the ear. However, ordinarily the waves in the two parts do not match when brought together and also the parts tend to separate unless greater skill is 40 exercised than that possessed by the average operator. The other alternative is to wave the hair over the bare ear which also leads to an imperfect performance by the average operator because the fingers must press the 45 hair against uneven surfaces and the comb tends to catch in them, and the conditions are entirely different from working against the scalp and tend to an imperfect result. All of this difficulty is remedied by my device 50 which gives at the ear a smooth firm surface to work against comparable to the scalp and enables any average operator to wave the hair at the ears as if highly skilled.

Continuing with the description of the mode of operation:—The hair at the other

ear having also been waved over a duplicate ear-covering device applied thereto, the next step is the heat treatment to dry the wetted hair to set the wave. During this step the devices are still kept in place on both ears. 70 The usual net may be placed over the head to prevent the streams of hot air from disturbing the wave. This takes a comparatively long time, especially to dry the hair at the ears in the ordinary method, whereas when the metallic ear covers are used the metal continuously takes up the heat and continuously reflects it back through the hair so that it dries there with remarkable quickness. The metallic cover cannot burn the user because it is held out of contact with the ear by the inner part 1. 75 80

For sanitary purposes, the inner part 1, readily detachable as shown and described, from the metallic plate 2 is thrown away 85 and substituted by a fresh one for each patron. This can be done without extravagance because the discarded parts are inexpensive; in fact, the whole device is inexpensive and remarkably efficient and makes it possible for any operator of only average skill to do excellent waving. 90

It will be understood that changes and modifications may be made in the foregoing other than those suggested and also that parts 95 may be omitted and added thereto without departing from the scope and spirit of the invention or from the scope and spirit of the claims.

What I claim is:

1. A device against which to wave the hair at the ear comprising a flexible plate larger in area than the ear and supportable to include the ear. 100

2. A device against which to wave the hair at the ear comprising a flexible metallic plate larger in area than the ear and supportable to include the ear. 105

3. A device against which to wave the hair at the ear comprising a metallic cover supportable to include the ear with its margin at the side of the head beyond the ear; and means for heat-insulating said cover from the ear. 110

4. A device against which to wave the hair at the ear comprising a metallic plate; and means associated with said plate for supporting it at the ear and for heat-insulating it from the ear. 115

5. A device against which to wave the hair at the ear comprising a metallic plate; and means associated with said plate for supporting it at the ear and for heat-insulating it from the ear, said plate and said means being releasably attached together. 120

6. A device against which to wave the hair at the ear comprising a metallic plate; and means associated with said plate for suspending it from the top of the ear and for heat-insulating it from the ear. 125

7. A device against which to wave the hair at the ear comprising a metallic plate at the side of the head adapted to include under it the ear; a pad of heat-insulating material co-extensive in area with the plate, said pad being attached to the plate and being located between it and the head; said pad next the ear having near its top a downwardly opening pocket adapted to hook over the upper part of the ear.

5
10 In witness whereof I have hereunto signed
my name this 4th day of Sept., 1930.

HELEN ALSTON TAYLOR.
